(57) **CLAIM**

The ornamental design for a cooling docking station, as shown and described.

DESCRIPTION

FIG. 1 is a perspective view illustrating a cooling docking station according to one embodiment;

FIG. 2 is a front view illustrating a cooling docking station according to one embodiment;

FIG. 3 is a back view illustrating a cooling docking station according to one embodiment;

FIG. 4 is a side view illustrating a cooling docking station according to one embodiment;

FIG. 5 is another side view illustrating a cooling docking station according to one embodiment;

FIG. 6 is a top view illustrating a cooling docking station according to one embodiment;

FIG. 7 is a bottom view illustrating a cooling docking station according to one embodiment;

FIG. 8 is a perspective back view illustrating a cooling docking station according to one embodiment; and,

FIG. 9 is a perspective front view illustrating a cooling docking station with a docked electronic device according to one embodiment.

The broken lines of the FIGURES are for illustration only. The broken lines and the unshaded regions bounded by broken lines form no part of the claimed design. The dot-dash broken lines define the bounds of the claim, which extends to the boundaries but does not include the boundaries; the broken lines in FIG. 9 showing an electronic device depict environmental subject matter only and form no part of the claim, while all other broken lines in the drawings depict portions of the cooling docking station that form no part of the claimed design. The unshaded surface between the broken line and the outside solid line on the back of the cooling docking station in FIG. 3 and FIG. 8 form no part of the claim. Non-oblique line shading is meant to show contour and not surface ornamentation.

1 Claim, 8 Drawing Sheets
